(57) **CLAIM**

The ornamental design for a fuel dispenser nozzle, substantially as shown and described.

DESCRIPTION

FIG. 1 is a perspective view of a new, original, and ornamental design of a fuel dispenser nozzle in accordance with the present invention;

FIG. 2 is a right side elevation view thereof;

FIG. 3 is a left side elevation view thereof;

FIG. 4 is a top side plan view thereof;

FIG. 5 is a bottom side plan view thereof;

FIG. 6 is a front side elevation view thereof; and,

FIG. 7 is a back side elevation view thereof.

The broken lines shown represent portions of a fuel dispenser nozzle and form no part of the claimed design.

1 Claim, 7 Drawing Sheets
